TALKING MACHINE AND THE LIKE

Filed Jan. 26, 1927

FIG. 1

FIG. 2

FIG. 3.

FIG. 5.

INVENTOR
FRANK ALLEN MITCHELL

BY
John F. Hanrahan
ATTORNEY

UNITED STATES PATENT OFFICE.

FRANK ALLEN MITCHELL, OF LONDON, ENGLAND, ASSIGNOR TO COLUMBIA PHONOGRAPH COMPANY, INC., OF BRIDGEPORT, CONNECTICUT, A CORPORATION OF NEW YORK.

TALKING MACHINE AND THE LIKE.

Application filed January 26, 1927, Serial No. 163,648, and in Great Britain November 19, 1926.

This invention relates to talking machines and the like, with more particular reference to portable or compact talking machines of the type disclosed in Patent No. 1,584,184, of May 5, 1926, it being understood, however, that the invention may be applied with equal effect and like advantage in connection with talking machines of other types.

The object of the present invention is to 10 provide simple and compact means for storing disc records within the casing of the instrument, and the invention comprises a record-holding device for use in combination with the lid of a talking machine, said means 15 in the embodiment shown, comprising a narrow hinged or pivoted metal or other member adapted to span the face of the records and hold them in place.

The invention also consists in a record-holding device for use in conjunction with talking 20 machines, comprising a hinged or pivoted framework adapted to hold the records in position while exposing the outside record disc.

The invention also consists in a record-holding device for use in combination with the lid of a talking machine consisting in a framework pivoted on members which may also be adapted to support the edges of the record 30 discs on both sides.

The invention still further consists in other details hereinafter described with reference to the following drawing, in which:

Fig. 1 is the side view of a portable talking 35 machine provided with a record carrier shown in its open position.

Fig. 2 shows the same record carrier closed and containing six record discs.

Fig. 3 is a face view of the same record carrier and shows the means for retaining the records in their correct lateral position.

Fig. 4 shows a similar record carrier of fancy design.

Fig. 5 is a detail view showing the construction and location of the bracket.

In carrying the invention into effect in one convenient manner, and as illustrated in Figs. 1 to 3, I provide a V-shaped metal or other frame 5 of such size as to completely span a record disc 6 as shown more clearly in Fig. 3. The frame is pivoted within the lid 7 of the case of a portable talking machine 8 in such a manner that the V is inverted and has its two

extremities 9 and 10 pivoted one on each inner side 11 of the lid 7 of the instrument.

The pivoted ends of the frame 5 are preferably attached to stamped, pressed or moulded brackets 12 and 13 formed in a suitable material, these brackets being screwed or otherwise fastened within the lid—one on each side of the record periphery at a distance of about 120° apart—and having inclined faces 14 formed thereon in such a manner that they will support record discs 6 resting thereon. Also, the portion 14a of the brackets act as a stop to limit the outward swinging movement of the frame 5, as best shown in Fig. 3.

The apex 15 of the V-shaped member is adapted to be engaged by a catch 16 which should preferably be spring controlled to retain the frame in its closed position within the lid of the instrument, as shown in Figs. 2 and 3. This catch is provided with a stop lug 16a to limit the inward movement of the V-shaped member or frame 5.

To operate the record container, the catch member 16 is first released and the apex 15 of the V-shaped frame 5 pulled forward, as shown in Fig. 1.

Record discs 6 to be stored are then placed 80 between the frame 5 and the inside of the cabinet lid 7 and they are retained in their correct lateral position in the lid by means of the two before-mentioned pivot bracket faces 14.

The frame 5 is then pushed back into place where it is held by the spring catch 16, thus retaining the records 6 between the two limbs of the member 5 (which spans the face of the record disc) and the inside of the lid of the 90 instrument.

When so held, the title label 17 of the outside record will be exposed to view between the limbs of the frame, this, besides giving the construction a neat appearance, also economizes the space within the cabinet, as there is no large obstruction between the record disc and the turn-table 18 and shaft 19 of the motor when the instrument is closed.

When it is desired that the tone-arm 20 100 and the sound-box 21 should be capable of being folded out of the way of the lid 7 when it is closed, arrangements may be provided for the purpose such as are described in my application about to be filed.

Fig. 4 shows an alternate construction for

the pivoted member 5 in which a fancy design is introduced as at 22. The frame 5 is pivoted at 9 and 10 to the side of the case 23 and is retained in position when closed by 5 the slide bolt 24 operating on the apex 15. The records 6 are retained in their lateral position by means of the projections 25 attached to the inside of the lid 7, the method of operation being the same as with the record-holding device described with reference to Figs. 1, 2 and 3.

It is obvious that the pivoted or hinged member may be of any other simple or fancy shape instead of the shapes described above— 15 it may be in the form of a simple strip, for example—also that the pivot bracket may be shaped in various ways or may be formed in the sides of the lid itself, and the record-supporting faces may be shaped and located 20 in any suitable way to maintain the record discs in their correct lateral position, and that the catch member may be in the form of a bolt, turn button or any other well-known latch device and may be adapted to operate 25 on any part of the record-retaining member.

It should be understood that the above description is by way of illustration and not limitation, and that the parts may be formed in any suitable material, although metal is 30 preferred.

Having now particularly described and ascertained the nature of my said invention, and in what manner the same is to be performed, I declare that what I claim is:

35 1. A record-holding device including means for engaging one surface of the record to be held, means pivoting said means and said pivoting means also adapted to support the edge of the record.

40 2. A record-holding device for use in con-

junction with talking machines, comprising a holding means adapted to hold the records in position while exposing the outside record disc, a pivot for mounting said holding means, and means associated with said pivot for supporting the lower edges of the record discs.

3. A record-holding device for use in combination with the lid of a talking machine, comprising a framework, means pivoting 50 said framework, and means associated with said pivoting means for supporting the lower edges of the record discs.

4. A record-holding device for use in combination with the lid of a talking machine, 55 the same comprising a framework, means pivotally mounting said framework, means to support the edges of the record discs, said pivoting means and said supporting means forming a unitary structure.

5. A record-holding device for use in combination with the lid of a talking machine, the same comprising a holding means, means pivotally mounting said holding means, and means associated with said mounting for 60 limiting the movement of said holding means in one direction.

6. A record-holding device for use in combination with the lid of a talking machine, the same comprising a holding means 70 means pivotally mounting said holding means, means associated with said mounting means for limiting the outward movement of said holding means, a catch for securing said holding means closed, and a stop associated 75 with said catch for limiting the inward movement of said holding means.

Signed at London, England, this 7th day of January, 1927.

FRANK ALLEN MITCHELL.
